GAME

Benjamin E. Mittelman, Chicago, Ill.

Application February 23, 1933, Serial No. 657,955

8 Claims. (Cl. 273—144)

The invention relates to games for amusement and more particularly to that type in which a series of tokens are simultaneously released to roll over successively a series of runways to produce an uncertainty in their order at the end of the course.

One object of the invention is to provide a game of this type in which the tokens can pass one another in the course of their travel with means for causing variation in their travel as a result of their transverse positions and to cause variation in the order of their arrival at the end of the course.

Another object is to provide improved and simple means for elevating the tokens from the end of the course to discharge them onto the beginning of the course.

Other objects will appear from the detailed description of the apparatus.

20 The invention consists of several novel features hereinafter set forth and more particularly set forth by claims at the conclusion hereof.

In the drawings:

25 Figure 1 is a perspective of an apparatus embodying the invention.

Figure 2 is a horizontal section.

Figure 3 is a section on line 3—3 of Fig. 4.

Figure 4 is a vertical section on line 4—4 of

30 Figure 3.

Figure 5 is a detail of the device for controlling the operation of the carrier for transferring the tokens from the top to the bottom of the course.

35 The invention is exemplified in apparatus which is enclosed in a rectangular casing 10 which is provided with a transparent front plate 11 through which the tokens will be visible as they run down and across the runway. The

40 course for the tokens is formed between a fixed cross wall 12 of the case and glass plate 11 by a series of inclined runways or strips 13 which extend inwardly from one side wall of the case and terminate short of the opposite side wall

45 and a series of downwardly inclined runways 14 which extend inwardly from the last mentioned side wall and terminate short of the first mentioned side wall. The inner ends of the runways 13 overlap the inner ends of the runways 14 and the series of runways form a zigzag or sinuous passage for the tokens so that they will roll successively along the uppermost runway 13 to its end, then gravitate onto the first

50 runway 14 and then drop off its inner end onto the next runway 13 and so on until they drop

off the lowermost runway 13. A series of balls 15 is used in playing the game. These may be of different colors or marked so that they will be distinguishable from one another. The runways are of sufficient width to permit one ball to pass another so that any ball which is moving with greater velocity can pass another if they happen to be side by side and not in alinement. To permit the balls to take longer or shorter courses according to their transverse positions 10 on the runways, some of the runways have portions of their inner ends offset or terminated so that balls running on the front and rear of the runway will drop off to the succeeding runway 15 before others and thus cause some balls to travel a shorter course or to be advanced ahead of a ball on a subjacent runway. In this manner, the order of the balls will be changed in their travel over the course. For this purpose the front portions of some of the runways are cut away 20 so they will terminate at 16 while the rear portions are extended beyond the point 16 and terminate as at 17. Some of these ends may be arranged to make it possible for a ball to entirely skip one runway and be advanced ahead 25 of another ball on the skipped runway. Others are arranged to permit only an interchange of order when one ball is traversing the portion of a runway adjacent one side after having rolled off an edge 17, by a succeeding ball passing off 30 one of the edges 16. This construction exemplifies a ball course in which the runways are formed to permit balls to pass one another side by side when they move at different velocities and which have their front and rear portions of 35 different lengths to effect a change in the order of the balls. The entire series of balls is simultaneously discharged through an opening 18 in the top portion of wall 12, onto the uppermost runway. From the lowermost runway the 40 balls fall successively onto a guideway 20 which has downwardly inclined ends and a central portion in front of an exit opening 21 formed in the wall 12. A transversely inclined deflector plate 21^a directs the balls in single succession 45 into opening 21. A wire 22 extends across the front of the opening 21 between the inner end of the deflector 21^a and the right hand end of slot 21 to hold the balls at the rear of opening 21 so they will be visible and so the order in 50 which they have arrived at the terminus of the course can be seen.

This mechanism is adapted to receive the entire series of balls at the lower end of the course and transfer them to and discharge them 55

through the delivery opening 18 above the uppermost runway. This mechanism comprises a rotatable carrier 23 which is fixed in a bearing 25 on the back wall of the case.

5 The operator can rotate shaft 24 by means of a crank 27 at one side of the case. Said crank is fixed to a shaft 28 which has affixed thereto a beveled pinion 26 which meshes with a beveled gear 29 on shaft 24. Each revolution of crank 10 27 will operate the carrier one-half revolution. The carrier is equipped with a pair of diametrically opposite pockets 30, 31 which have front openings normally registering with the openings 18, 21 in plate 12. These pockets have a back 15 wall and inclined top and bottom walls so that when either pocket registers with the receiving opening 21, the balls will roll backwardly by gravity and be retained in the pocket. When either pocket is in its elevated position, it will be inverted so that the balls will roll forwardly 20 out of the carrier through opening 18 and drop onto the uppermost runway 13 when that pocket is moved into registry with that opening. A gate 32 is provided to close opening 18 during the 25 movement of the carrier so the balls cannot be released until the entire set is positioned to pass through opening 18 to cause substantially simultaneous release of the balls. This gate is pivoted at 33 to the wall 12, is normally pressed downwardly by a spring 35 against a stop 34 and has a flange or abutment 36 which is adapted to be 30 engaged by either of the cams 37 on the carrier. Normally the gate 32 is positioned below the opening 18. During the rotation of the carrier, the cam 37 approaching said opening will engage flange 36 and lift the gate to close said opening until that cam clears the flange 36 at which time the gate will be snapped downwardly 35 to clear opening 18. This occurs when the pocket is fully in registry with opening 18. When the 40 pocket arrives in registry with the opening 18, the entire set of balls will roll out of the pocket through said opening and drop onto the uppermost runway. As one of the carrier pockets is moved to deliver the balls to the runways the other pockets will be rotated into registry with the exit opening 21 in readiness to receive the balls after they have descended along the runways. If desired, a similar gate 32^a may be 45 provided to close the opening 21 and hold the balls in the lower carrier pocket until said pocket has cleared the opening 21. Gate 32^a is pressed upwardly by a spring 32^b and has a flange 32^c which is engaged by the cams 37 to hold said gate downwardly to clear the opening 21 until the carrier has started to rotate. After 50 it has been started, the cam will pass over the flange 32^c and permit the spring 32^b to lift the gate.

60 To limit the carrier to cycles of one-half revolution, a double arm 38 is fixed to shaft 24 and a pivoted detent 39 is adapted to successively arrest said arms and position the carrier at the end of each operation. This detent may be coin-controlled or otherwise.

65 This construction exemplifies a rotatable carrier comprising pockets for transferring a set of tokens from one end of the course to the other and whereby the tokens will be automatically discharged onto the course by one pocket. Also a rotatable carrier by which these pockets will be alternately and simultaneously shifted into receiving and discharging positions.

70 The invention is not to be understood to be restricted to the details set forth since these 75

may be modified within the scope of the claims without departing from the spirit and scope of the invention.

Having thus described the invention, what I claim as new and desired to secure by Letters 5 Patent, is:

1. In a game, the combination of a case, a series of rolling tokens, a series of downwardly inclined runways arranged successively to receive the tokens from one another, one of the runways being wider than the tokens to permit them to assume different transverse positions thereon, and having its lower end formed to vary the length of the run of the tokens thereon when they run on different transverse portions. 10

2. In a game, the combination of a case, a series of rolling tokens, and a series of superposed downwardly inclined runways arranged successively to receive the tokens from one another, one of the runways being wider than the 20 tokens to permit them to assume different transverse positions thereon, and having its lower end formed to vary the length of the run of the tokens thereon when they run on different transverse portions, and means for simultaneously 25 discharging the series of tokens to the uppermost runway.

3. In a game, the combination of a case, a series of rolling tokens, a series of superposed, downwardly inclined runways arranged successively to receive the tokens from one another, one of the runways being wider than the tokens to permit them to assume different transverse positions thereon, and having its lower end formed to vary the length of the run of the 30 tokens thereon when they run on different transverse portions, and means for transferring the series of tokens from a point below to a point above the runways. 35

4. In a game, the combination of a case, a series of rolling tokens, a series of downwardly inclined runways arranged successively to receive the tokens from one another, the runways being of sufficient width to permit the tokens to pass one another thereon, one or more 45 of said runways having its lower end formed to vary the length of the run of the tokens thereon when they run on different transverse portions, and means for transferring the series of tokens from a point below the runways to 50 a point above them.

5. In a game, the combination of a case, a series of rolling tokens, and a series of downwardly inclined separated runways arranged successively to deliver the tokens from one to 55 another, one of the runways being wider than the tokens to permit them to assume different transverse positions thereon, and having its lower end provided with relatively offset portions to vary the length of the run of the 60 tokens thereon when they run on different transverse portions.

6. In a game, the combination of a case provided with a transparent front wall, a parallel wall in the rear of the transparent wall, a series 65 of rolling tokens, the rear wall being provided with a lower opening for discharge of the tokens, and with an upper inlet opening for the tokens, a series of downwardly inclined runways arranged to receive the tokens through the inlet 70 opening and successively to pass the tokens from one another and of sufficient transverse width to permit one token to pass another, and a carrier provided means to receive the tokens after they pass through the lower opening and to 75

transfer them collectively to the upper opening, one or more of the runways having portions of their discharge ends relatively offset to discharge tokens thereon at different points.

5 7. In a game of the character described, the combination of a case provided with a transparent front wall, a parallel wall in the rear of the transparent wall, a series of rolling tokens, the rear wall being provided with a bottom discharge opening and upper inlet opening for said tokens, a series of downwardly inclined runways mounted on the front face of said parallel wall and arranged to receive the tokens successively from one another, a rotatable carrier adjacent the back face of said parallel wall provided with a pocket adapted to receive the tokens after they have passed through the discharge opening, and in response to rotation of the carrier to discharge the tokens through the inlet opening onto the uppermost runway, a normally open gate for the inlet opening pivoted adjacent the rear face of said parallel wall so that it may be swung upwardly into a closed position, and means associated with the carrier operative during rotation of the latter to swing the gate upwardly into its closed position when the pocket approaches said inlet opening and to release the gate so that it swings downwardly into its open position when the pocket is brought into registry with the inlet opening.

10 8. In a game of the character described, the

combination of a case provided with a transparent front wall, a parallel wall in the rear of the transparent wall, a series of rolling tokens, the rear wall being provided with a bottom discharge opening and upper inlet opening for said tokens, a series of downwardly inclined runways mounted on the front face of said parallel wall and arranged to receive the tokens successively from one another, a rotatable carrier adjacent the back face of said parallel wall provided with a pocket adapted to receive the tokens after they have passed through the discharge opening, and in response to rotation of the carrier to discharge the tokens through the inlet opening onto the uppermost runway, a gate for closing the inlet opening pivoted adjacent the rear face of the parallel wall so that it may be swung upwardly from an open position into a closed position with respect to said inlet opening, a spring applied to the gate to hold the same in its open position, and a cam connected to the carrier and arranged to shift the gate upwardly against the force of the spring into its closed position when the pocket during rotation of the carrier approaches the inlet opening and to release the gate so that it is swung into its open position by the spring when the pocket is brought into registry with said inlet opening.
